UNITED STATES PATENT OFFICE.

WILLIAM S. STUCKENBERG, OF INDIANAPOLIS, INDIANA, ASSIGNOR TO THE
METAL BOUND PACKAGE COMPANY, OF CHICAGO, ILLINOIS.

METHOD OF MANUFACTURING PACKAGE MATERIAL.

SPECIFICATION forming part of Letters Patent No. 653,323, dated July 10, 1900.

Application filed November 13, 1899. Serial No. 736,744. (No specimens.)

To all whom it may concern:

Be it known that I, WILLIAM S. STUCKENBERG, a citizen of the United States, residing in Indianapolis, in the county of Marion and 5 State of Indiana, have invented a new and useful Improvement in Methods of Manufacturing Package Material, of which the following is a specification.

Fabrics for the manufacture of open or ventilated shipping crates and packages have been heretofore made consisting of a series 10 of parallel separated slats with transverse binder-wires stapled to the slats and uniting them together, and such a fabric is shown in 15 the patent to Greenstreet, No. 547,486, and a machine for attaching the slats to the wires is shown in the patent to the same inventor, No. 579,574.

My invention relates to the method of manufacture of fabrics of this class, although it 20 was more specially devised for the manufacture of a fabric in which the slats were secured to binders made of band-iron by means of tongues integral with the bands and 25 punched from them and then driven through the slats and clenched. The slats used in these fabrics have heretofore been cut from what is known as "veneer" stock—that is to say, stock about one-fourth inch or less in 30 thickness—and they have been so cut while the sheet of veneer was yet hot and moist from the log. In my invention instead of first severing the sheet-veneer into slats, as has heretofore been the practice, I take a 35 sheet of freshly-cut veneer having sufficient width to form all the slats required in a single piece of the fabric and as the first operation secure the binders, whether the same are wire or band-iron, transversely across one 40 face of the sheet, using fasteners such as have been heretofore employed for attaching the severed slats to the binders and locating the fasteners precisely as they have been located heretofore—that is to say, so they will serve 45 to attach the individual slats into which the sheet is subsequently converted properly to the binders. I then score or nearly sever the sheet upon the face thereof opposite to that to which the binders are applied along equi- 50 distant lines and between the binder-fasten-

ings, thereby, in effect, dividing the sheet into slats, but without wholly severing them from each other. The sheet thus scored and attached to the binders is now allowed to dry and the shrinkage which then occurs completes the separation of the slats along the lines at which the sheet had been scored, and thereby forms the ventilating-spaces required in the fabric. This scoring may be easily and quickly done by machinery, and it will be noticed that my invention saves the handling of the individual slats.

The accompanying drawings show at Figure 1 a perspective of the sheet of veneer from which a section of the fabric is produced. 65 Fig. 2 is an inside view of the same after the binders have been applied thereto. Fig. 3 shows the same after scoring. Fig. 4 is an edge view of the scored sheet; and Fig. 5 is a similar view of the scored sheet after drying, 70 the latter view being partly in section.

Referring to the drawings, 6 represents the wet unscored sheet of veneer, and 7 7 the binders, of which there may be any number desired. The binders here shown are of band-iron and the sheet is attached thereto by tongues 8 8, punched out of the binders and forced through the sheet and clenched, as clearly illustrated at Fig. 5. The scoring is 75 shown at 9 9 and passes nearly through the sheet, but does not effect a complete severation, the completing of the severation being effected by the shrinkage, as already explained.

I claim—

The method of manufacturing package material from green or wet wood sheets, consisting in applying thereto transverse metal binders and attaching such binders to the sheet at intervals corresponding to the width of the 90 desired slats, then scoring the sheet between the fastenings, and then allowing the sheet to dry, whereby the shrinkage completes the severation along the lines of the scoring and converts the sheet into separated and spaced 95 slats, substantially as specified.

WILLIAM S. STUCKENBERG.
